UNITED STATES PATENT OFFICE.

HARRY WEISKOPF; OF CHICAGO, ILLINOIS.

SAMPLE-MOUNTING MACHINE.

No. 872,872.

Specification of Letters Patent.

Patented Dec. 3, 1907.

Application filed June 18, 1907. Serial No. 379,582.

To all whom it may concern:

Be it known that I, HARRY WEISKOPF, a citizen of the United States of America, residing at Chicago, in the county of Cook and 5 State of Illinois, have invented new and useful Improvements in Sample-Mounting Machines, of which the following is a specification.

This invention relates to machines for 10 mounting sample strips upon cards or folders, designed more particularly for use in attaching paint samples to cards but which is capable of other uses, and one of the principal objects of the same is to provide a machine which can be quickly adjusted to apply any suitable number of sample strips to cards or folders by an unskilled person.

Still another object is to provide a machine of the character referred to which can be operated by a foot treadle in contradistinction 15 to a power operated machine.

Another object of the invention is to apply sample strips to cards at the desired distances apart after said cards have received 20 paste applied thereto by a machine forming the subject matter of a separate application filed under date of August 11, 1906, Serial 25 No. 330,226.

The foregoing advantages and objects are 30 attained by means of the construction illustrated in the accompanying drawings, in which:

Figure 1 is a front to rear sectional view of a machine made in accordance with this invention. Fig. 2 is a transverse vertical section of the upper portion of the same. Fig. 3 is a detail plan view of the table portion of 35 the machine.

Referring to the drawings for a more particular description of my invention, *a* designates the framework for supporting the table *b* which is secured to the upper portion of 40 said framework, said table having a series of openings *c* therein, said openings conforming 45 in size and relative arrangement to the size and arrangement of the sample strips to be attached to the cards.

Below the openings in the table a movable plunger board *d* is arranged, said board being 50 supported upon a treadle rod *e* connected at its lower end to a pivoted treadle *f*. The rod

e near its upper end passes through an aperture *g* in a board or plate *h* and a spiral spring *i* surrounds the rod and bears at its upper end against the under surface 55 of said board or plate and the lower end of said spring rests upon a stop or collar *j* secured to the rod. Supported upon the plunger board *d* are a series of blocks *k* which fit accurately within the openings *c* in the 60 table.

Feeding guides *l* are secured to the table to accurately hold the card in place. A platen *m* hinged at *n* to the table and formed of a comparatively heavy metal plate, is adapted 65 to be swung down to lie upon the top of the card after it has been placed within the guides *l*. When the treadle *f* is operated the blocks *k* are carried upward through the perforations *c* in the table to apply the top series 70 of strips placed within said openings and resting upon the said blocks. The platen *m* is then lifted from the card and swung back against the stop *o* and the card is removed 75 from the machine with the sample strips attached thereto.

It will be obvious from the foregoing that a machine made in accordance with my invention will be simple in construction, can be operated by a person without skilled knowledge, can be readily adjusted to apply strips at varying distances apart upon cards by a proper arrangement of the strips and the machine is capable of rapid operation and with a little practice a person can apply a great 85 number of sample strips to cards on the machine described.

Having thus described the invention, what I claim is:

The herein described machine for mounting sample strips upon cards, comprising a frame, a table supported upon the frame and provided with a series of apertures therethrough; a weighted platen hinged to the table, a stop for said platen, a series of guides 90 on said table to hold the paper sheets in position to receive the sample strips, a plunger board, a series of presser blocks secured to said board and projecting into the apertures in said table, a board or plate rigidly secured 95 to the frame under said plunger board, a plunger rod extending through said board 100

and connected to said plunger board, a spring surrounding said plunger rod and bearing at its upper end against said board or plate, a supporting collar on said plunger rod for the 5 opposite end of said spring, and a foot treadle to which the lower end of said plunger rod is pivoted.

In testimony whereof, I affix my signature in presence of two witnesses.

HARRY WEISKOPF.
